UNITED STATES PATENT OFFICE.

DANIEL M. HOLMES, OF CINCINNATI, OHIO.

CAKE-MACHINE.

SPECIFICATION forming part of Letters Patent No. 249,938, dated November 22, 1881.

Application filed October 8, 1881. (No model.)

To all whom it may concern:

Be it known that I, DANIEL M. HOLMES, of Cincinnati, in the county of Hamilton and State of Ohio, have invented a new and useful Improvement in Cake-Machines, of which 5 the following is a full, clear, and exact description, reference being had to the annexed drawings, forming part of this specification.

My invention relates to an improvement in 10 machines for making dough into cakes; and it has for its object to secure an even and constant feed and pressure to the valves and cutters.

The improvement consists in a novel 15 construction and arrangement of parts, as herein-after described.

In the accompanying drawings, Figure 1 is 20 a side elevation of a cake-machine; Fig. 2, a plan view of a portion of the machine, with the hopper and packer removed; Fig. 3, the packer; Fig. 4, a vertical section, and Fig. 5 a detail view.

With the use of the ordinary dough-box and plunger in cake-machines considerable time is 25 lost in the intermittent action of the feed. I have therefore provided the herein-described means of accomplishing an even and constant feed and delivery, whereby the time usually consumed in recharging the machine is saved, 30 and a consequently larger yield of goods in a given time is effected.

In the drawings, A represents the frame of the machine. G is the driving-pulley, attached to the shaft P, upon which is secured the chain- 35 pulley H, which, by means of the chain O, drives the pulley H', secured upon shaft m. A pinion, M, secured to the latter shaft, meshes with the gear-wheel K, which is provided with adjustable bearings, and through this wheel 40 communicates motion to the shaft f. The shaft f is supported in suitable bearings at the top of the machine in front of an iron chamber, Z, having a series of openings, z, and is provided with as many beveled pinions D as there are 45 openings in the said chamber. Through the said openings in the chamber Z project a series of shafts, D', having on their projecting ends corresponding beveled pinions D², which are

adapted to mesh with the pinions D. The inner ends of the shafts D' are provided with 50 screw-propellers C, and the said propellers are adapted to communicate with the usual detachable delivery-chamber, R, through an opening in the chamber Z.

Above the propellers C, and at right angles 55 thereto, is arranged a shaft, a, supported in bearings formed in the walls of the chamber Z, and provided with a series of radial teeth, a', which are adapted to be rotated through slots formed in a plate, B, which is secured in 60 a horizontal position by means of a flange upon the rear wall of the chamber Z. A hopper, E, is secured above the chamber Z, and communicates therewith through the open top of the latter.

The chamber R is provided with the usual 65 cutters, which are operated by means of cams upon shaft P.

The operation of the machine is as follows: The shaft a is rotated by means of the gearing shown in the drawings, so that its teeth will pass up through the slots in the plate B. The plate thus serves as a scraper for the teeth to prevent the dough, which is fed in at the hopper, from being carried round by the 75 teeth, and the dough is thus fed to the propellers and packed closely thereon. The revolving of the propellers carries the dough into the delivery-chamber R, from which it is delivered in the form of cakes by means of the 80 cutters or valves, used as in the ordinary machines.

Having thus described my invention, what I claim as new, and desire to secure by Letters 85 Patent, is—

1. In a cake-machine, the combination, with the delivery-chamber R and its cutters, of the chamber Z, propellers C, toothed shaft a, slotted plate B, and suitable gearing for the said shaft and propellers, substantially as and for 90 the purposes set forth.

2. In a cake-machine, the combination of the chamber Z, having a series of openings, z, the propellers C, supported through said openings and provided with bevel-pinions D², the 95 shaft f, having intermeshing pinions D, the

toothed shaft *a*, and slotted plate B, substantially as shown and described.

3. In a cake-machine, the combination of the hopper E, the chamber Z, open at the top 5 for receiving the dough, the toothed shaft *a*, and slotted plate B, adapted to serve as a scraper, the series of propellers C, arranged at right angles to the said shaft through openings in the chamber, and suitable gearing for 10 operating the said shaft and propellers, substantially as shown and described.

4. In a cake-machine, the combination of a series of propellers arranged in a suitable chamber and provided with suitable gearing, of a toothed shaft arranged at right angles thereto 15 and adapted to pack the dough round the propellers, substantially as shown and described, and for the purposes specified.

DANIEL M. HOLMES.
